UNITED STATES PATENT OFFICE.

SYDNEY BUCKLEY, OF PHILADELPHIA, PENNSYLVANIA, ASSIGNOR TO NILES-BEMENT-POND COMPANY, OF NEW YORK, N. Y., A CORPORATION OF NEW JERSEY.

BRIDGE FOR TRAVELING CRANES.

1,296,758.

Specification of Letters Patent.

Patented Mar. 11, 1919.

Application filed June 2, 1917, Serial No. 172,425.

Renewed January 7, 1919. Serial No. 270,060.

To all whom it may concern:

Be it known that I, SYDNEY BUCKLEY, a citizen of the United States, and a resident of Philadelphia, in the county of Philadelphia and State of Pennsylvania, have invented certain new and useful Improvements in Bridges for Traveling Cranes, of which the following is a specification, reference being had therein to the accompanying drawings.

The invention relates more particularly to traveling cranes of the class in which each comprises a movable bridge having two parallel separated elements respectively carrying rails. A hoisting mechanism is provided which consists of a trolley movable along the rails on the bridge and depending load engaging elements which usually extend between the two elements of the bridge.

The invention relates especially to the bridge elements of cranes of the type specified, and a construction embodying my present invention is in some respects similar to the construction disclosed and claimed in my copending application for cranes, Serial No. 149,180, filed February 17, 1917. In the design of cranes, in order to meet the various and different requirements as concerns span, capacity, character of load, operating conditions, etc., it is necessary to vary the character of the bridge construction. The object of the present invention is to provide a bridge construction of the general type set forth in my aforesaid copending application but which is adapted to meet different requirements.

In the accompanying drawings I have illustrated the embodiment of the invention which I now deem preferable, but it will be understood that the construction shown is intended to be merely illustrative and is not intended to define or limit the scope of the invention. Particularly it will be understood that the shapes of the structural sections used, the means for connecting the several members together and the various structural details can be varied widely in accordance with the requirements of any particular case or in accordance with the preferences of the designer.

Of the drawings:

Figure 1 is a side elevation of a crane embodying the invention, some of the parts to which the invention does not directly relate being omitted.

Fig. 2 is a transverse vertical sectional view, the part at the left being taken along the line 2-2 of Fig. 3 and the part at the right being taken along the line 2A-2A of Fig. 3.

Fig. 3 is a longitudinal vertical sectional view taken along the center line of one of the bridge elements.

Fig. 4 is a fragmentary plan view of one of the bridge elements, certain of the parts being broken away to show other parts.

Referring to the drawings, particularly to Figs. 1 and 2, it will be observed that I have shown a crane comprising a traveling bridge which is carried at its ends on trucks which travel along rails 1, 1 supported on suitable elevated structures 2, 2. The bridge is made up of two longitudinal elements arranged with a space between them. The two elements are connected at the ends by suitable transverse members 3 as shown in Fig. 2. Preferably there is provided a separate two-wheeled truck element 4 for each end of each bridge element.

For the purpose of moving the crane as a whole along the rails 1, 1, one or more truck wheels at each end of the bridge are connected with a suitable driving motor. As illustrated, one of the truck wheels at each end is connected with a gear wheel 5 which meshes with a pinion 6 on a shaft 7 which extends longitudinally from one end of the bridge to the other. A motor 8 is provided for rotating the shaft 7, thus serving to move the bridge in one direction or the other as required.

Supported on each of the said longitudinal bridge elements is a rail 9. A suitable trolley or hoisting mechanism is provided which is supported on the rails 9, 9, and is adapted to travel along them. The hoisting mechanism as a whole is represented in the drawings by 10, but as this hoisting mechanism of itself constitutes no part of the present invention, detailed description thereof can be omitted. It is sufficient to point out that the hoisting mechanism is provided with a suitable load-engaging device such as the hook 11 which is suspended by a cable or cables 12, passing through the space between the two longitudinal elements of the bridge. By means of a motor 13 the rope can be wound upon or unwound from a drum 14, thus causing the hook with its load to be raised or lowered.

There is a suitable cage 15 which is provided with space for an operator and with suitable controlling devices whereby the movements of the bridge and of the hoisting mechanism can be started, stopped and controlled as required.

The present invention relates primarily to the construction of the two main side elements of the bridge, and as these elements 10 are similar to each other it will be sufficient to describe but one of them in detail. In the drawings many of the structural details are omitted or are incompletely shown, as these constitute no part of the invention and 15 can be varied as desired.

In the construction presented in my aforesaid application Serial No. 149,180, each side element of the bridge comprises two separated individually complete main girders 20 and a supplemental rail-carrying girder located between the main girders. The present construction differs from the aforesaid construction primarily in the provision of a unitary main girder instead of two 25 individually complete main girders. The main girder comprises two separated upper compression members and a single combined lower tension member. A rail-carrying girder is positioned between the upper members 30 of the main girder and is suitably supported.

In the drawings, the two upper members of each main girder are indicated by 16 and 17 respectively, and, as shown, each of these 35 members comprises two angle bars arranged with their horizontal flanges uppermost and a vertical plate secured between the vertical flanges of the bars. The lower tension member of each main girder is indicated by 18, 40 and, as shown, this comprises four angle bars arranged with their horizontal flanges in contact, a vertical plate being secured between the vertical flanges of the bars. The three longitudinal members 16, 17 and 18 45 are connected at their ends to suitable end structures 19, 19.

The upper longitudinal members of each girder are connected with the lower longitudinal member by means of diagonal truss members 20 and 21. These diagonal bars are shown as being in the form of channels.

Positioned between the longitudinal members 16 and 17 of each girder and at approximately the level thereof, is a rail-carrying girder 22. This is shown as being in the form of an I-beam. To each of these girders 22 one of the rails 9 is secured. Each rail-carrying girder 22 is suitably connected with the longitudinal members of 60 the corresponding main girder and preferably it is directly connected with each longitudinal member, although my invention is not limited in this respect. As illustrated, transverse members 23, 23 extend transversely at intervals from one to the other 65

of the upper members 16 and 17. One of the transverse members is preferably located in each transverse plane where the diagonal members 20 and 21 are connected with the upper longitudinal members. As 70 illustrated, each transverse member 23 is in the form of an I-beam which extends through a suitable notch formed in the rail-carrying I-beam 22.

For providing further support for the 75 rail-carrying I-beam, I provide vertical members 24 extending from the lower longitudinal member 18 to the rail-carrying beam. Each vertical member is preferably located midway between two of the transverse members 23 and at a point where the lower member 18 is joined by the diagonal members 20 and 21.

It will be observed that in some respects this construction is more simple than that set 80 forth in my copending application above referred to. The construction is such that at least a part of the rail load can be transmitted directly to the main girder by means of simple compression members such as the 85 members 24, 24.

What I claim is:

1. A traveling crane bridge element comprising two spaced upper longitudinal compression members, a single centrally located 95 lower longitudinal tension member, diagonal truss members connecting the two upper members with the single lower member, a rail carrying girder positioned centrally between the two upper members, and means 100 for supporting the rail carrying girder from the longitudinal members.

2. A traveling crane bridge element comprising two spaced upper longitudinal compression members, a single centrally located 105 lower longitudinal tension member, diagonal truss members connecting the two upper members with the single lower member, a rail carrying girder positioned centrally between the two upper members, and supports 110 for the rail carrying girder extending upward from the lower longitudinal member.

3. A traveling crane bridge element comprising two spaced upper longitudinal compression members, a single centrally located 115 lower longitudinal tension member, diagonal truss members connecting the two upper members with the single lower member, a rail carrying girder positioned centrally between the two upper members, and supports 120 for the rail carrying girder extending transversely between the two upper longitudinal members.

4. A traveling crane bridge element comprising two spaced upper longitudinal compression members, a single centrally located 125 lower longitudinal tension member, diagonal truss members connecting the two upper members with the single lower member, a rail carrying girder positioned centrally be- 130

tween the two upper members, supports for the rail carrying girder extending upward from the lower longitudinal member, and additional supports for the rail carrying girder extending transversely between the two upper longitudinal members.

5. A traveling crane bridge element comprising vertically spaced upper and lower longitudinal compression and tension mem-

bers, diagonal truss members connecting the 10 longitudinal members, a centrally positioned rail carrying girder, and load transmitting members for connecting the rail carrying girder directly to both the upper and the lower longitudinal members.

15

In testimony whereof, I hereto affix my signature.

SYDNEY BUCKLEY.
